UNITED STATES PATENT OFFICE.

ALBERT BECK, OF CHICAGO, ILLINOIS, ASSIGNOR TO MCGILL TICKET PUNCH COMPANY, OF CHICAGO, ILLINOIS, A CORPORATION OF ILLINOIS.

PUNCH.

1,417,488.

Specification of Letters Patent. Patented May 30, 1922.

Application filed October 24, 1919. Serial No. 333,039.

To all whom it may concern:

Be it known that I, ALBERT BECK, a citizen of the United States, and a resident of Chicago, in the county of Cook, State of Illinois, have invented certain new and useful Improvements in Punches.

My invention relates to punches, particularly hand punches for punching tickets, cards, etc.

One of the important objects of the invention is to provide such a punch of such construction that the major portion thereof may be formed integrally from a sheet metal stamping and in which the male and female die elements are both secured or accurately guided on the main or body member of the punch so that accurate co-operation of the die elements is at all times assured. Another object of the invention is to provide in such a punch improved hinging arrangement of the punch members which will give increased punching leverage and which will strengthen the construction. Another object of the invention is to provide a punch, preferably of sheet metal, although not necessarily so made, of such construction that the cards, sheets, or other material inserted in the punch are clearly visible so that it can be accurately determined just where punching will take place.

The above and other features of my invention are incorporated in a punch shown in a certain preferred embodiment on the accompanying drawing in which

Fig. 1 is a side elevational view,
Fig. 2 is a vertical sectional view,
Fig. 3 is an enlarged sectional view on plane 3—3, Fig. 2,

Fig. 4 shows the stamped blank from which the body member of the punch is formed up and

Fig. 5 is an enlarged plan view of the die plate.

The main part of the body member A is formed up from a single piece of sheet metal, the stamped blank before forming being shown in Fig. 4. The blank has the main or central portion 10, the side parts 11 and 12 and the end or grip part 13. The side parts are separated from the main part by the slots 14 and 15. After punching of the blank to the shape shown in Fig. 4 it is bent longitudinally substantially along the lines *a* and *b* and the side parts 11 and 12 are bent along the lines *c* and *d*. After such

bending the edges *e* and *f* are secured together as by welding. The bending along the lines *a*, *b*, *c* and *d* is preferably gradual so as to give greater strength. Inserted between the sides 11 and 12 after bending of the blank is the plate 16. The plate is inserted between the upper ends of the side walls and has the front and rear flanges 17 and 18 extending downwardly against the inturned lower ends of the side walls, the enclosure or chamber *g* being then provided. The plate 16 has the opening 19 for receiving the die hub 20 on the die plate 21, this plate being secured by means of the screws 22.

In the sides of the body part of the stamped blank and at the front thereof are the notches 23 and 24 into which the horizontal guide plate 25 is secured after bending of the blank. This plate has the hole 26 therethrough in vertical register with the hole 27 in the die hub 20, and in the top wall of the member A is the guide hole 28. In the holes 26 and 28 the die pin 29 is guided with its axis at all times coincident with the axis of the die hole 27. Both the male and female die members are thus supported on the main or body member A of the punch.

The die pin operating member B of the punch is also formed integral of sheet metal and comprises the back portion 30 and the strengthening side flanges 31 and 32. The front end 33 of the member B extends between the side walls of the member A above the slots 14 and 15 while the outer end 34 deflects downwardly to be opposite the grip section 13 of the body member A. At its front end the member B has the longitudinally extending slot 35 which receives the reduced section 36 of the die pin 29. A short distance rearwardly of the slot 35 the flanges of the member B have openings 37 for receiving the hinge or pivot pin 38 which is secured in the openings 39 and 40 of the member A. When the member B is swung the die pin 29 is given axial movement. A suitable spring 41 interposed between the rib sections 13 and 34 tends to hold the grip ends apart and the die pin 29 in its upper position to clear the slots 14 and 15 for the entrance of material to be punched. When the grip sections are brought together the pin 29 is shifted vertically downwardly into the die hole 27 and the inserted material is accurately punched.

The die pin is always at right angles with the die hub 20 and the member B of the punch has no direct connection with the pin but merely causes axial movement there-
5 of, the pin being entirely supported and guided on the member A which also supports the die hub 20. As the member B is not directly secured to the pin 29 the pivot pin 38 can be placed close to the end of the
10 member, and the punching leverage is thus greatly increased.

Referring to Fig. 4, the said blank has the notch 42 at the front of the body part and in front of the hole 28 provided for the die pin.
15 When the punch is formed up the top of the member A in front of the die pin is open so that the punching operation can be readily observed and the material to be punched accurately aligned with reference to the die
20 pin. To facilitate such observation a slot 43 may be provided in the plate 25 in front of the pin guiding hole 26. The wall sections 44 and 45 adjacent the slot 42 are triangular and form the guide surfaces 46 and 47 for
25 guiding the material into the punch.

At the outer edges of the side sections 11 and 12 of the blank are the rectangular recesses 48 and 49 which join when the member A is bent into form to provide an outlet
30 opening from the chamber g. A sliding cover 50 is provided for this outlet, this cover being deflected at its side to provide grooves 51 and 52 for receiving the ridges 53 and 54 on the sides 11 and 12 of the mem-
35 ber A. The cover can be shifted along the ridges or beads to expose or to close the outlet 48-49, and transverse projections 55 and 56 limit the shifting movements of the cover. Normally the cover is in closed po-
40 sition so that the punchings are retained in the compartment g. When it is desired to discharge the accumulated punchings the cover is slid rearwardly and the punchings shaken out at the outlet opening.

45 The ridges or beads 53 and 54, besides serving as rails for the cover, also serve to strengthen the side walls 11 and 12, and the beads are preferably carried around the rear ends of the slots 14 and 15 to strengthen the
50 member A where the greatest strain is apt to occur during operation of the punch.

I thus produce a strong and efficient punch in which the die members are at all times accurately relatively aligned and the male
55 die member is always at right angles with the female die member.

I have shown and described a preferred embodiment of my invention in which I employ a stamping of sheet metal. By employing
60 a sheet metal stamping in the construction of my punch, I am enabled to make a very considerable saving in labor and material without sacrificing rigidity, strength, or other necessary qualities which are essential in such a punch. By my improved form

of punch I am enabled to dispense with considerable difficulty in the manufacture and assembly of parts or elements heretofore entering into the construction of punches.

I do not desire to be limited to the exact 70 construction, arrangement and operation shown and described as modifications are no doubt possible which will still come within the scope of the invention.

I claim as follows:

1. In a punch of the class described, the combination of a body member provided with a slot for receiving a ticket or the like, a die secured in the body member on one side of said slot, a die pin reciprocally mounted in said body member on the other side of said slot, and a lever pivoted in said body member and operatively connected with said die pin whereby said pin may be moved into and out of said die, said body member having a 80 sight opening, permitting accurate placing of the ticket in said slot whereby the part to be punched may be placed under the die pin.

2. In a punch of the class described, the 90 combination of a body member, having a slot dividing it into upper and lower portions, said lower portion enclosing a punching receiving chamber, a die opening in the upper wall of said lower portion, a die pin reciprocable on 95 the upper portion of said body member, a lever pivoted on said body member for effecting shifting of said pin, said chamber in said lower portion having an outlet, ridges extending longitudinally along the sides of said lower portion, and a cover for said outlet having grooves in its side walls for receiving said ridges whereby said cover may be slid back and forth on said lower portion to open or close said outlet.

3. In a punch of the class described, the combination of a body member, a punching receiving chamber, a die opening in the upper wall of said body member, a die pin reciprocable on said body member, a lever pivoted on said body member for effecting shifting of said pin, said chamber in said body member having an outlet, ridges extending longitudinally along the sides of said body member, and a cover for said outlet having grooves in its side walls for receiving said ridges whereby said cover may be slid back and forth on said body member to open or close said outlet.

4. In a punch of the class described, the combination of an integral body member stamped from sheet metal and formed so as to provide a slot for receiving a ticket or the like, and having a bottom portion disposed below said slot, a plate disposed below said slot and having its ends bent downwardly into engagement with said bottom portion thereby providing a closed compartment, a die secured in said plate, a die pin reciprocally mounted in said body member on the 120 125 130

other side of said slot and a lever pivoted in said body member and operatively connected with said die pin whereby said pin may be moved into and out of said die.

5 5. In a punch of the class described, the combination of an integral body member stamped from sheet metal and formed so as to provide a slot for receiving a ticket or the like, a die secured in the body member 10 on one side of said slot, a plate secured in the body member on the other side of said slot, said plate and body member on that side of the slot having registering openings disposed opposite said die, a die pin reciprocally mounted in said openings, and a lever pivoted in said body member and operatively connected with said die pin whereby said pin may be moved into and 15 out of said die.

60 by providing a receptacle for punchings, said receptacle having an outlet for said punchings, a closure member for said outlet, said housing and closure member having cooperating means to permit relative movement of the closure member, a die in said plate, a die pin reciprocally mounted in said housing on the other side of said slot and a lever pivotally mounted in said housing and operatively connected with said die pin whereby said pin may be moved into and 65 out of said die.

65 70 9. In a punch of the class described, the combination of an integral body member stamped from sheet metal and formed so as

20   6. In a punch of the class described, the combination of an integral sheet metal stamping formed so as to provide a housing and a grip portion, said housing being provided with a slot for receiving a ticket, or
25   the like, a member disposed below said slot in said housing and adapted to form a closed receptacle for punchings, a die in said member, a plate secured in the housing on the upper side of said slot, said plate and housing on the upper side of said slot having registering openings disposed opposite said die, a die pin reciprocally mounted in said openings, and a lever pivotally mounted in said housing and operatively connected with
30   said die pin whereby said pin may be moved into and out of said die.

35   stamped from sheet metal, and formed so as to provide a housing and a grip portion, 75
40   said housing being provided with a slot for receiving a ticket or the like, a plate disposed below said slot in said housing, thereby providing a receptacle for punchings, said receptacle having an outlet for said 80
45   punchings, a closure member for said outlet, one of said members being provided with beads and the other of said members being provided with grooves, said beads being adapted to slide in said grooves, a die 85
50   in said plate, a die pin reciprocally mounted in said housing on the other side of said slot, and a lever pivotally mounted in said housing and operatively connected with said die pin whereby said pin may be moved into 90
55   and out of said die.

40 7. In a punch of the class described, the combination of an integral body member stamped from sheet metal, and formed so as to provide a housing and a grip portion, said housing being provided with a slot for receiving a ticket or the like, a plate disposed below said slot in said housing, thereby providing a receptacle for punchings, said receptacle having an outlet for said punchings, a closure member for said outlet, a die in said plate, a die pin reciprocally mounted in said housing on the other side of said slot, and a lever pivotally mounted 45 in said housing and operatively connected with said die pin whereby said pin may be moved into and out of said die.

45 10. In a punch of the class described, the combination of an integral body member stamped from sheet metal and formed so as to provide a slot for receiving a ticket or 95 the like, a die secured in the body member on one side of said slot, a die pin reciprocally mounted in said body member on the other side of said slot, and a lever pivoted in said body member and operatively connected with said die pin whereby said pin may be moved into and out of said die, said body member having a sight opening, permitting accurate placing of the ticket in said slot. 100

50 105

In witness whereof, I hereunto subscribe my name this 22nd day of October. A. D.

8. In a punch of the class described, the combination of an integral body member 55 stamped from sheet metal, and formed so

as to provide a housing and a grip portion, said housing being provided with a slot for receiving a ticket or the like, a plate disposed below said slot in said housing thereby providing a receptacle for punchings, 60 said receptacle having an outlet for said punchings, a closure member for said outlet, said housing and closure member having cooperating means to permit relative movement of the closure member, a die in said plate, a die pin reciprocally mounted in said housing on the other side of said slot and a lever pivotally mounted in said housing and operatively connected with said die pin whereby said pin may be moved into and 65 out of said die. 70

9. In a punch of the class described, the combination of an integral body member stamped from sheet metal, and formed so as to provide a housing and a grip portion, 75 said housing being provided with a slot for receiving a ticket or the like, a plate disposed below said slot in said housing, thereby providing a receptacle for punchings, 80 said receptacle having an outlet for said punchings, a closure member for said outlet, one of said members being provided with beads and the other of said members being provided with grooves, said beads being adapted to slide in said grooves, a die 85 in said plate, a die pin reciprocally mounted in said housing on the other side of said slot, and a lever pivotally mounted in said housing and operatively connected with said die pin whereby said pin may be moved into 90 and out of said die.

10. In a punch of the class described, the combination of an integral body member stamped from sheet metal and formed so as to provide a slot for receiving a ticket or 95 the like, a die secured in the body member on one side of said slot, a die pin reciprocally mounted in said body member on the other side of said slot, and a lever pivoted in said body member and operatively connected with said die pin whereby said pin may be moved into and out of said die, said body member having a sight opening, permitting accurate placing of the ticket in said slot. 100 105

In witness whereof, I hereunto subscribe my name this 22nd day of October, A. D. 1919.

ALBERT BECK.
